Primary Examiner — Karen E. Eldridge Powers*Assistant Examiner* — Jasmine Mlinarcik(74) Attorney, Agent, or Firm — Andrus Intellectual Property Law, LLPCLAIM

The ornamental design for a brassiere, as shown and described.

DESCRIPTION

FIG. 1 is a front perspective view of an embodiment of a brassiere according to my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front view thereof showing the brassiere in an alternate position; and,

FIG. 9 is a back view of the brassiere in the alternate position shown in FIG. 8.

The portions of the brassiere shown in broken lines represent environmental structure that forms no part of the claimed design.

1 Claim, 6 Drawing Sheets(56)
